METAL BUILDING STRUCTURE

George P. Hoffman, Jacksonville, Fla.

Application June 11, 1936, Serial No. 84,741

13 Claims. (Cl. 189—1)

This invention relates to a new type of metal building that may be assembled at the site from shop-formed sheets and punched angles without rivets or welds and with a minimum use of bolts, 5 screws or other fastening means.

The invention aims to provide a simple and readily erected metal building having adequate provision for weather proofing and protection from heat and cold for moderate climates.

10 Other objects and advantages of the invention appear in connection with the following description of the illustrative embodiment shown in the accompanying drawings, wherein

Fig. 1 is a perspective view of an interior corner 15 of a two story building, partly in vertical cross-section along two planes at right angles to the walls and floors;

Fig. 2 is a detail view drawn to a larger scale, showing a cross-section of the foundation and 20 lower portion of a side wall, on the line 2—2 in Fig. 1, looking in the direction of the arrows;

Fig. 3 is a horizontal cross-section through the side walls at a corner, on the line 3—3 in Fig. 1;

Fig. 4 is a vertical cross-section through a side 25 wall and floor, on the line 4—4 in Fig. 1;

Fig. 5 is a vertical cross-section of the floor, taken on the line 5—5 in Fig. 4 at right angles to the latter;

Fig. 6 is a vertical cross-section through a 30 corner of a side wall at the roof, showing a modified design; and

Fig. 7 is a perspective view of a corner of the building showing the parts of the side walls, floor and ceiling disassembled in their relative positions 35 to illustrate the manner of construction and assembly.

Figs. 3, 4, 5 and 6 are drawn to the same scale.

The building shown in the drawings is a two 40 story and roof structure of rectangular plan having a concrete foundation and first floor, and metal sides, second floor, ceilings and roof, with such weatherproofing and insulation as is required by the climate, location and purpose for which it is designed.

45 The foundation 11 and ground floor 12 may be formed of concrete laid directly on the ground or in a suitable excavation, the outer edge of the foundation at the floor line being beveled off and provided with an inverted trough shape ridge 13 projecting slightly above the floor and providing a support for the lower edges of the horizontally disposed outer wall sections 14. The inner wall sections 15, which are vertically disposed, are supported at their lower ends on channels 16 50 laid on the floor just inside of the ridge 13, with

their vertical legs facing inwards and their horizontal legs secured by bolts 17, as shown in Fig. 2. The lower ends of the inner wall sections 15 are preferably secured to the channels by screws 18 of suitable type. An asphalt strip 19 or other 5 waterproofing means, is laid on the ridge 13 between it and the V-shape flanges 19 with which the outer wall sections 14 are formed.

Both the outer wall sections 14 and the inner 10 wall sections 15 are trough shape in cross-section, being formed with flanges 19, 20 along their edges, respectively, and as shown best in Fig. 7, the flanges 20 of the inner wall sections are provided with inclined notches or slots 21 to receive the downwardly bent edges of the flanges 19 on the outer wall sections, the inner and outer wall sections being arranged with their flanged faces towards each other so as to be concealed in the wall. The ends of the outer wall sections are mitered at the corners of the building (see Figs. 3 20 and 7) and may be covered with angles 22 secured thereto by suitable means, such as pointed screws inserted through punched holes in the angles and driven and screwed into the sheet metal beneath.

The joints between the flanges of the outer 25 wall sections may be filled with any suitable plastic waterproofing material either at the time of erection or later, but the shape of these flanges in itself prevents water from entering the walls except under most severe conditions. No filling is 30 needed between the flanges of the inner wall sections, although they may be filled with roof cement, putty, or other plastic material wherever they do not abut closely because of imperfections 35 in workmanship or damage in handling or erecting.

Openings for doors and windows may be formed 40 of lengths and widths corresponding to multiples of the width of the wall channels by omitting portions of such of these channels as may be desired. These openings are suitable for receiving door and window frames of usual construction and made either of wood or of metal, but as these frames form no part of my invention they 45 are not shown in the drawings.

The floors are composed of trough shape lower 50 sections 24 and inverted trough shape upper sections 25, laid at right angles to each other and supported at their ends on the upper ends of the vertical wall sections 15. The side flange 26 along one edge of each lower floor section 24 has an inturned edge 27 to give the flange additional stiffness and thus strengthen the section as a whole. These flanges and the side flanges 28 of 55

the upper floor sections are provided with slots 29 to receive the similarly slotted flanges of the mating floor sections, as shown in detail in Figs. 4, 5 and 7.

5 The floors are protected around their outer edges by the outer wall panels 14, which cover any openings at the ends of the channel shape floor sections, and they may be spaced therefrom sufficiently to prevent conduction of heat 10 and cold directly to the floor sections. The ends of the upper tier of inner wall sections rest directly on the top faces of the upper floor sections, and any partitions desired may be rested directly on the floor sections, which are stiff 15 enough to bear a considerable load thus distributed across them. Channels 30 are advantageously used for securing the ends of the inner wall sections 15 to the floor sections, and these channels may be attached to the adjacent sheet 20 metal sections by screws in like manner to the channels 22. The upper ends of the lower tier of inner wall sections may be secured to the floor likewise if desired.

A ceiling is provided consisting of inverted 25 trough shape sections 34 provided with plain flanges 35 for stiffening them and supporting wood or metal strips 36 to which the ceiling sheets 37 are attached by nails or other suitable fasteners. The ceiling supporting strips 36 are 30 preferably wedge shape and held in dovetail notches 38 in the flanges 35. The ceiling sections 34 run across the room in one direction only, being supported on their ends by channels 39 screwed to the inner side wall sections 15, as 35 shown in Fig. 4. A sheet 40 of felt, building paper or other sound deadening means may be placed between the floor and ceiling if desired.

The roof is similar to the floor in its construction, comprising lower and upper trough 40 shape channels 44, 45, supported at their ends on the sides and ends of the wall sections 14, 15, as shown in Fig. 1. The upper ends of the inner wall sections 15 are cut along diagonal lines to conform to the pitch of the roof if it is 45 not perfectly flat, and an angle 41 is secured thereto and to the ends of the roof section for holding them together and assisting in supporting the roof.

In the modified design shown in Fig. 6, the 50 roof is flat and covered with a layer of insulating and waterproofing material 42 protected by a layer of sheet metal 43 or other suitable surface covering or coating; and the outer wall sections 14 are lined with insulating board 46 or other 55 form of non-conducting material, to prevent sweating and rusting on their inner sides.

The invention has many advantages in addition to its simplicity and inherent strength and rigidity. The double wall and roof construction 60 largely prevents sweating on the inner wall, as the inner and outer sections touch only at the intersections of their flanges and the inner wall remains substantially at the same temperature as the inside of the building when the temperature 65 drops outside.

The horizontal exterior wall sections with their inverted V flanges provide adequate protection 70 against driving rain and water from the roof, and such condensation of moisture as occurs on their inner sides is caught in these flanges and prevented from dripping down the inside of the walls. The downwardly inclined edges of the flanges of the outer wall sections also lock the inner and outer sections together as they are 75 assembled, thereby dispensing with screws, bolts

or other fastenings through the exterior walls that water might find its way through.

The vertically disposed inner wall sections with their deep flanges provide the necessary strength 5 for supporting the outer sections and the upper floors, ceilings and roofs, and these flanges also aid in preventing entrance of the wind and weather, as the narrow cracks between them may readily be filled with plastic cement or other waterproofing material after they have 10 been assembled. Where these inner sections stop at a floor level, the outer sections are continuous from below to above the floor, thereby concealing and protecting the edges of the 15 floors.

The two way trough shape floor sections form a stiff floor supported from all four sides and do away with the need for floor beams and other frame members in buildings having the interior space divided into rooms of not over 20 eighteen to twenty feet in length and breadth by bearing partitions of similar construction to the outer walls. The floor sections are so arranged that the lower sections 25 with the strengthened flanges 26, 27, extend in the direction 25 of the shorter span.

In the pitch type of roof, the lower trough shape sections extend up and down the slope to catch any water that may come through the roof and convey it over the flanged outer wall 30 section and off at the eaves, as illustrated in Fig. 1, the ends of these lower panels extending slightly over the eaves for this purpose.

The invention lends itself readily to changes in the form and arrangement of the walls and 35 floors, and obviously is capable of adaptation to many different kinds of small buildings. The invention is not restricted to the details of construction shown.

What I claim is as follows:

1. A metallic building structure comprising 40 trough shape side wall sections arranged in horizontal tiers on the outside and in vertical rows on the inside of the wall structure, the edge flanges of said sections abutting within the wall 45 structure with the flanges of the respective tiers of horizontal sections in endwise alignment at the corners and mitered to fit, whereby the ends of the outer sections project beyond and support the edge flanges of the inner sections at the corners, and means for securing said aligning ends 50 together.

2. A metallic building structure comprising 55 horizontally disposed flanged outer sections arranged in tiers with their flanges abutting on the inside of the wall, vertically disposed flanged inner sections arranged in a row with their flanges abutting on the inside of the wall, the flanges of said inner sections being notched to receive the adjacent edges of the flanges of the outer sections 60 extending transversely thereof to retain said outer and inner sections spaced from the edges of the flanges of the opposite sections, respectively, means for preventing disengagement of said flanges from said notches, means 65 for supporting the lower ends of said vertically disposed sections, and a floor or roof structure overlapping the upper ends of said vertically disposed sections and supported thereby, whereby 70 said vertically disposed sections tie said structure together with the intervening spaces in communication throughout both vertically and horizontally.

3. A metallic building structure comprising 75 horizontally disposed flanged outer sections ar-

- ranged in tiers with their flanges abutting on the inside of the wall, vertically disposed flanged inner sections arranged in a row with their flanges abutting on the inside of the wall, some of said flanges being notched to receive the adjacent edges of the flanges of the sections extending the other way, means for preventing disengagement of said flanges from said notches, means for supporting the lower ends of said vertically disposed sections, and a floor or roof structure overlapping the upper ends of said vertically disposed sections and supported thereby, one of said horizontal sections covering and protecting the outer edge of said floor or roof.
5. A metallic building structure comprising interengaging flanged sections in its side walls arranged in horizontal tiers on the outside to prevent entrance of the weather, vertically disposed inner side wall lower sections provided with stiffening flanges notched to receive the flanges of the outer sections, a metallic floor supported on the upper ends of said inner side wall lower sections and supporting in turn the lower ends of inner side wall upper sections, the outside wall sections being supported thereby in interengaging relationship from bottom to top across the outer edges of said floor.
6. A metallic building structure comprising interengaging horizontally disposed flanged sections forming the outer face of its side walls, said sections having their flanges inwardly disposed and provided with down-turned edges, vertically disposed flanged sections forming the inner face of its side walls having their flanges facing towards the outer wall sections and provided with downwardly inclined notches into which the edges of the flanges on the outer sections engage to retain the sections in assembled position.
7. A metallic building structure comprising interengaging horizontally disposed flanged sections forming the outer face of its side walls, said sections having their flanges inwardly disposed, vertically disposed flanged sections forming the inner face of its side walls having their flanges facing towards the outer wall sections and provided with notches into which the edges of the flanges on the outer sections engage to retain the sections in assembled position, the depths of said notches being less than the width of the flanges on the inner sections and the inner edges of the flanges of the outer sections being spaced from the inner wall sections, and means for supporting the lower ends of said inner wall sections.
8. A metallic building structure comprising flanged sections in its side walls arranged in horizontal tiers on the outside to prevent entrance of the weather, vertically disposed inner side wall lower sections provided with stiffening flanges notched to receive the flanges of the outer sections, a metallic floor supported on the upper ends of said inner side wall lower sections and supporting in turn the lower ends of inner side wall upper sections, the outside wall sections being supported thereby in abutting relationship from bottom to top, and an inclined roof overlapping and supported on the upper ends of said inner side wall upper sections, the upper ends of said inner side wall upper sections being cut at an angle to suit the inclination of the roof.
9. A metallic wall structure comprising horizontally disposed flanged outer sections arranged in tiers with their body portions in vertical alignment and flanges abutting on the inside of the wall, said flanges being continuous to form unbroken joints between said sections, vertically disposed flanged inner sections arranged in a row with their flanges abutting on the inside of the wall and spaced from the body portions of said outer sections, some of said vertical flanges being notched to receive the adjacent edges of the flanges of the horizontal sections, means for preventing disengagement of said flanges from said notches, and means for supporting the lower ends of said vertically disposed sections.
10. A metallic building structure comprising side walls formed of two series of trough shape sections having their edge flanges facing towards the inside of the wall, the outer sections being arranged with their flanges in contact horizontally, and the inner sections being arranged with their flanges in contact vertically, and spaced notches in the edges of the flanges of the inner sections alining with the flanges of the outer sections and adapted to receive the latter to form a rigid hollow wall, having no metallic contact between the inner and outer sections except at said notches.
11. A metallic building structure comprising side walls formed of two series of trough shape sections having their edge flanges facing towards the inside of the wall, the flanges on the outer sections being inverted V-shape in their position of assembly and said sections being arranged with their flanges in contact horizontally, and the inner sections being arranged with their flanges in contact vertically, and spaced notches in the edges of the flanges of the inner sections inclined to conform to the slant of the flanges on the outer sections and adapted to receive and hold the latter against outward movement when assembled to form a rigid hollow wall.
12. A metallic floor structure comprising two series of trough shape sections extending cross-wise of the building from side wall to side wall in both directions, the sections of one series being disposed with the flanges uppermost and the sections of the other series being disposed above the first series with their flanges underneath and resting on the first series, the flanges of the first series having their extremities bent horizontally to underlie and support the trough portions of the second series, and notches in the edges of the flanges of both series to provide for interengagement thereof to form a rigid structure.
13. A metallic roof structure comprising two series of trough shape sections extending cross-

- wise of the building from side wall to side wall in both directions, the sections of one series being disposed with the flanges uppermost and the sections of the other series being disposed above the first series with their flanges underneath and resting on the first series, the flanges of the first series having their extremities bent horizontally to underlie and support the trough

portions of the second series, and notches in the edges of the flanges of both series to provide for interengagement thereof to form a rigid structure, and a layer of waterproofing material supported by the trough portions of said second series.

GEORGE P. HOFFMAN.
